UNITED STATES PATENT OFFICE.

HANS ROEDER, OF BERLIN, GERMANY.

PENHOLDER.

SPECIFICATION forming part of Letters Patent No. 740,181, dated September 29, 1903.

Application filed March 16, 1903. Serial No. 148,107. (No model.)

To all whom it may concern:

Be it known that I, HANS ROEDER, a subject of the King of Prussia, German Emperor, residing at 123 Ritterstrasse, Berlin, Kingdom of Prussia, German Empire, have invented certain new and useful Improvements in Penholders, of which the following is an exact specification.

My invention relates to improvements in penholders, and has for its purpose to avoid a damaging of the holder by the different forms of the shafts of the pens.

In order to make my invention more clear, I refer to the accompanying drawings, in which—

Figure 1 shows a longitudinal section of the upper part of the penholder. Fig. 2 is a view of the elastic tube to be fixed in a bore of the upper part of a penholder. Fig. 3 is a section of the tube and the pin situated within the same with a small pen-shank shifted in. Fig. 4 is the same section with a broad pen-shank shifted in.

As will be seen from the drawings, the elastic tube *d*, situated within a bore of the penholder *g*, has not the same diameter all over, as is the case in the constructions hitherto used; but the diameter of the same is smaller in the middle part *a* of the same. The tube *d* is provided with a plurality of slots *b*.

It will be seen from Fig. 2 that the slots *b* do not reach up to the upper edge of the tube, as is usually the case, but are closed on both ends. Within the tube a pin *e* is situated, which is advantageously provided with a cap *f* of larger diameter. The pin *e* may consist of wood; but it will be understood that instead of the wood pin a hollow metal pin or the like

may be used. In order to fix the tube in the holder, small barbs *h* are provided at the lower end of the same, which allow a shifting in of the tube, but prevent the falling out of the same.

If the shank of the pen is shifted in between the pin *e* and the tube *d*, the small metal strips situated between the single slots *b* are pressed outward, as may be seen from Figs. 3 and 4. The number of these small strips depends upon the breadth of the pen-shank.

By this construction any form of pen-shank can be fixed in the holder and held fast by the springs formed by the strips between the slots *b* of the tube *d*, and the splitting of the wood of the holder resulting from shifting in of pens with broader shanks, as is frequently the case in other constructions, is also prevented.

Having thus fully described the nature of this invention, what I desire to secure by Letters Patent of the United States is—

In a penholder, the combination with the holder, of a tube situated within the same, the diameter of which tube is smaller in the middle part than at the ends of the same, said tube being provided with longitudinal slots closed at both ends, and a pin situated within this tube, substantially as described and for the purpose as set forth.

In witness whereof I have hereunto signed my name, this 2d day of March, 1903, in the presence of two subscribing witnesses.

HANS ROEDER.
